1 Claim, 1 Drawing Sheet

FIG. 1

FIG. 2

UNITED STATES PATENT AND TRADEMARK OFFICE

Certificate

Patent No. D. 392,930

Patented: March 31, 1998

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Rick Pruden, Torrance, Calif.

Signed and Sealed this Sixth Day of October, 1998.

JAMES GANDY
Supervisory Patent Examiner
